SPECIFICATION forming part of Design No. 24,730, dated October 1, 1895.

Application filed August 31, 1895. Serial No. 561,157. Term of patent 3½ years.

To all whom it may concern:

Be it known that I, EMIL G. SAUER, a citizen of the United States, and a resident of Brooklyn, in the county of Kings and State of New York, have invented a new and original Design for Carpets and Borders, known as "Pattern No. 4,772," of which the following is a specification.

This invention comprises two parts— namely, the design A for a carpet and the design B for a border; and I do hereby declare that the drawings accompanying this specification conveys to any one a clear understanding of the same and is sufficient to enable such a person to use my invention.

The design A is characterized by continuous conventional outline scrolls constituting its leading feature.

The design B is characterized by a panel

of continuous-outline scroll-work having outer scrolls enlarged, constituting its leading feature.

What I claim, and desire to secure by Letters Patent, is—

1. In a design for a carpet, the body A, substantially as shown.
2. In a design for a carpet, the border B, substantially as shown.
3. The design for a carpet, comprising the body A and the border B, substantially as shown.

In testimony whereof I have signed my name to this specification in the presence of two subscribing witnesses.

EMIL G. SAUER.
